(Cl. D34—5)

To all whom it may concern:

Be it known that we, Raymond T. Gutz and Anne Swainson, citizens of the United States, residing at Park Ridge, county of Cook, State of Illinois, and Chicago, county of Cook, State of Illinois, respectively, have invented a new, original, and ornamental Design for Croquet Racks, of which the following is a specification, reference being had to the accompanying drawing, forming a part thereof.

In the drawing:

We claim:

The ornamental design for a croquet rack, substantially as shown.

RAYMOND T. GUTZ.
ANNE SWAINSON.
